DESIGN FOR A COMBINED MARKING INSTRUMENT AND STAND

Samuel A. Harris, Winston-Salem, N. C.

Application April 26, 1946, Serial No. 128,986

Term of patent 14 years

(Cl. D74—24)

To all whom it may concern:

Be it known that I, Samuel A. Harris, a citizen of the United States, residing at Winston-Salem, in the county of Forsyth and State of North Carolina, have invented a new, original, and ornamental Design for Combined Marking Instrument and Stand, of which the following is a specification, reference being had to the accompanying drawing, forming part thereof.

Figure 1 is a side elevational view of a combined marking instrument and stand, showing my new design.

Figure 2 is a side elevational view similar to Figure 1 but showing the marking instrument separated from the stand.

Figure 3 is an elevational view looking in the direction of the arrow *a* in Figure 1, and

Figure 4 is a view looking in the direction of the arrow *b* in Figure 1.

I claim:

The ornamental design for a combined marking instrument and stand, as shown.

SAMUEL A. HARRIS.
